(57) **CLAIM**

We claim the ornamental design for a wristband health tracker, as shown and described.

DESCRIPTION

FIG. 1 is an isometric view of a wristband health tracker looking at the top, front, and right sides.

FIG. 2 is a further isometric view of the wristband health tracker looking at the top, back, and right sides.

FIG. 3 is a further isometric view of the wristband health tracker looking at the bottom, back, and left sides.

FIG. 4 is a further isometric view of the wristband health tracker looking at the bottom, front, and left sides.

FIG. 5 is a right side view of the wristband health tracker.

FIG. 6 is a left side view of the wristband health tracker.

FIG. 7 is a top view of the wristband health tracker.

FIG. 8 is a bottom view of the wristband health tracker.

FIG. 9 is a front view of the wristband health tracker.

FIG. 10 is a back view of the wristband health tracker; and, FIG. 11 is an isometric view of the wristband health tracker looking at the top, front, and right sides.

Dashed and dotted lines are used for illustrative purposes only to give environmental context to the claimed design and do not form any part of the claimed design. In the context of this ornamental design, portions of the design in question are made of a compliant material that may flex into a bracelet or wristband shape, as shown in FIG. 11 (which is provided for context). Stipple shading is used in FIGS. 1 through 11; the stipple shading is not to be understood as conveying a particular surface finish, but is used to convey surface contouring. A portion on the top side of the wristband health tracker that does not have the diagonal ridge pattern on the wristband portions is a translucent, clear, or clear, tinted material, as indicated by the diagonal line hatching on that portion.

1 Claim, 7 Drawing Sheets
